UNITED STATES PATENT OFFICE.

HARRY F. HITNER, OF MOUNT VERNON, OHIO, ASSIGNOR TO PITTSBURGH PLATE GLASS COMPANY, A CORPORATION OF PENNSYLVANIA.

DEVICE FOR SPLITTING GLASS.

1,296,661.

Specification of Letters Patent. Patented Mar. 11, 1919.

Application filed June 26, 1916. Serial No. 105,926.

To all whom it may concern:

Be it known that I, HARRY F. HITNER, a citizen of the United States, residing at Mount Vernon, in the county of Knox and 5 State of Ohio, have invented a certain new and useful Device for Splitting Glass, of which the following is a specification.

The invention relates to a means adapted for splitting glass, and particularly glass 10 cylinders, by electricity. It has for its principal objects, the provision of a device (1) having improved means for making the contacts with the thin band or splitting ribbon of high resistance material employed, and 15 one in which the burning in two of the band at these points is prevented, (2) having an improved and simplified wiring arrangement and (3) having an improved means for preventing short bends and consequent 20 breaking of the supply wires. One embodiment of the invention is illustrated in the accompanying drawings, wherein—

Figure 1 is a side elevation of the device; Fig. 2 is a partial side elevation on an enlarged scale of the connecting means at one 25 end of the device; and Figs. 3, 4, 5 and 6 are sections on the lines III—III, IV—IV, V—V and VI—VI of Fig. 1.

Referring to the drawings, 1 is the framework of the device having an operating portion 2 at one end and a handle portion 3 at the other end. This framework comprises a channel iron, and into its face is fitted a strip of refractory insulating material 4, 35 preferably asbestos. Lying over this asbestos strip 4 is the splitting band or ribbon 5 of a relatively high resistance material, preferably of the alloy of nickel and chromium known as nichrome.

40 The left-hand end of the framework is provided with a spring member 6 having its end 7 bent at a right angle and pointed, as indicated in Fig. 2. The end of the spring 6 carries a contact block 8, preferably of brass or similar material, held in position by 45 means of the screws 9. The block 8 is provided with a transverse groove 10 adjacent its forward end, and the end of the band 5 is clamped in this groove by the pointed end 50 7 of the spring 6. I have found this method of connection involving the use of the groove and the pointed clamping end of great advantage since the contact thus provided is most effective and the burning off of the 55 ribbon at this point is avoided. The spring

6 serves to apply any desired amount of tension to the band 5.

The right-hand end of the band is clamped against a block 11 by means of a spring 12 and a pair of screws 13 and 14, 60 the block being grooved and the method of connection being the same as that just described and illustrated in connection with Fig. 2. The block 11 is held in position by means of the stud 15 and nut 16 (Fig. 4) and, 65 the block, stud, and nut insulated by the members 17, 18 and 19, as shown in Fig. 4.

The handle portion of the frame is provided with a pair of terminal blocks 20 and 21 to which the wires of the cable 22 are attached by means of the screws 23 and 24. The block 21 is held to the handle portion by the stud 25 and is grounded on the framework so that current supplied at this point flows through the framework to the block 75 8 at the left-hand end of the framework. The other terminal block 20 is secured in position by means of the stud 26 and nut 27 and is insulated from the handle portion 3 by means of the members 28, 29 and 30, as 80 illustrated in Fig. 5. This insulated terminal block 20 is connected by means of the wire 31 (Fig. 1) with the other insulated block 11 (Fig. 4) lying at the right-hand end of the splitting ribbon 5.

85 It will be seen that the foregoing constitutes a simple wiring arrangement, since all that is necessary is the insulation of the blocks 11 and 20 and their connection by means of the wire 31, the other electrical 90 connections being provided by grounding the blocks 8 and 21 upon the metal framework.

95 Secured to the handle portion 3 of the framework is the guard member 32 having its end 33 opposite the terminal blocks 20 and 21 and provided with a perforation 34 for the passage of the cable 22. This guard is preferably made of U-shape in cross-section, as indicated in Fig. 6, and is held in place by means of the screw 35. This member protects the wires against breakage at their points of attachment to the terminal blocks 20 and 21 since the portion 33 of the guard allows only a slight backward and forward movement of the cable, the principal bending occurring in the cable at the point 36, and such curve is much less abrupt than that which occurs where the wires are secured to the terminal blocks.

What I claim is:

1. In an electrical splitting device, a support, a metal terminal block carried thereby, a high-resistance band adapted to be heated electrically to a relatively high temperature, means for securing one end of the band to the block, means for securing the other end of the band to the support, a contacting surface on the block intermediate the points at which the band is secured, and means for applying tension to the band to hold it in engagement with said contacting surface.
2. In an electrical splitting device, a metal terminal block carried thereby, a high-resistance band adapted to be heated electrically to a relatively high temperature, means for securing the band to the block, a contact surface on the block over which said band is bent and lying between the means for securing the band to the block and the other end of the band, and means for applying tension to the band to hold the bent portion in engagement with the contact surface.
3. In an electrical splitting device, a metal terminal block, a spring carrying said block, a high resistance band adapted to be heated electrically to a relatively high temperature, means for clamping the end of the band to the block, and a contact surface on the block engaging said band, and lying between said clamping means and the other end of the band, said spring being arranged to apply tension to the band to hold it in engagement with the contact surface.
4. In an electrical splitting device, a metal terminal block provided intermediate its ends with a transverse groove, a high resistance band fixed at one end and having its other end extending across the groove, a clamping edge for forcing the band into the groove, and means for yieldingly forcing the block away from the fixed end of the band to cause the band to yieldingly engage the block in advance of the clamping edge.
5. In an electrical splitting device, a metal terminal block provided intermediate its ends with a transverse groove, a high resistance band having one end extending across the groove and contacting with the block in advance of the groove, a leaf spring for applying tension to the band having its end bent so as to provide a clamping edge for the band at said groove, and clamping means for causing said edge to bend the band into said groove, the said band yieldingly engaging the block intermediate the groove and the other end of the band, whereby overheating of the edge and the band at the point of bending is avoided.
6. In an electrical splitting device, a terminal block of metal having a transverse groove, a flat high resistance band having its end extending transversely across the groove, and a spring clamping means for carrying the block and for applying tension to the band and having a pointed edge for engaging the band opposite the groove.
7. In an electrical splitting device, a terminal block of metal having a groove, a flat high resistance band fixed at one end and having its other end extending transversely across the groove, and a spring clamping means for carrying the block and for applying tension to the band and having a pointed edge for engaging the band opposite the groove, the said band being bent over a part of the block in advance of the said edge.

HARRY F. HITNER.
